UNITED STATES PATENT OFFICE.

CARLO ZORZI, OF MILAN, ITALY.

ELECTRODE.

1,310,727.

Specification of Letters Patent. Patented July 22, 1919.

Application filed June 29, 1918. Serial No. 242,630.

To all whom it may concern:

Be it known that I, CARLO ZORZI, a subject of the King of Italy, residing at Milan, Kingdom of Italy, have invented certain new and useful Improvements in Electrodes, of which the following is a specification.

The present invention relates to improvements in electrodes; and it comprises an article of the general class or character indicated which is made up of a plurality of separate elements arranged in superposed relation in the form of a pile, and so constructed as to conduct the liquid or gaseous products of electrolytic decomposition to a single receiving vessel.

An electrode embodying the invention is illustrated diagrammatically in vertical section in the accompanying drawing, and comprises, as shown, a superposed series of open-topped elements D mounted coaxially and in spaced relation upon vertical supports H which, in turn, are fixed to a base G of conducting material. These elements D are in the form of truncated cones or pyramids of uniform size and shape, which may have either plane or wavy surfaces; and each of them is provided with an encircling cap or ring E of insulating material, which is connected to it intermediate its upper and lower edges. The uppermost element D is connected directly to the lower end of a vertical collector pipe C, into which the products of decomposition pass, this pipe C being encircled by a vertical sleeve I which is substantially co-extensive with it and constitutes an integral continuation of the uppermost cap E. The upper end of pipe C has connected to it the down-turned end of a pipe T, through which the liquid or gaseous products of decomposition pass on their way to the receiving vessel.

The spacing of the several elements D from one another, provides passageways or channels between them, through which and through the open tops of said elements the decomposition products pass toward and into the collector pipe C, being guided and facilitated in their passage by means of the truncated shape of said elements and also, to some extent at least, by the somewhat similarly-shaped caps E. The electrode, as a whole, is disposed within a suitable electrolytic bath, which, as will be understood, exerts a decomposing action upon the mate-

rial of which the elements D are constructed, and it is as a result of this action that the decomposition products are obtained.

I claim as my invention:

1. An electrode of the character specified, comprising a series of centrally-apertured elements, and vertical supports whereon said elements are mounted one above another in spaced parallel relation, with their apertures disposed in coaxial alinement, the spaces between adjacent elements forming guide channels for conducting the liquid or gaseous products of electrolytic decomposition to and through the apertures in said elements.

2. An electrode of the character specified, comprising a series of open-topped, truncated elements, and vertical supports whereon said elements are mounted one above another, in spaced, parallel relation, with their open tops disposed in coaxial alinement, the spaces between adjacent elements forming guide channels for conducting the liquid or gaseous products of electrolytic decomposition to and through the open tops of said elements.

3. An electrode of the character specified, comprising a series of centrally-apertured elements, a cap of insulating material encircling each of said elements and connected thereto, and vertical supports whereon said elements are mounted one above another in spaced, parallel relation, with their apertures disposed in coaxial alinement, the spaces between adjacent elements forming guide channels for conducting the liquid or gaseous products of electrolytic decomposition to and through the apertures in said elements.

4. An electrode of the character specified, comprising a series of centrally-apertured elements, vertical supports whereon said elements are mounted one above another in spaced, parallel relation, with their apertures disposed in co-axial alinement, the spaces between adjacent elements forming guide channels for conducting the liquid or gaseous products of electrolytic decomposition to and through the apertures in said elements, and a collector pipe connected at its lower end to the uppermost element and into which said products pass from that element.

5. An electrode of the character specified,

comprising a series of open-topped, truncated elements, vertical supports whereon said elements are mounted one above another in spaced, parallel relation, with their 5 open tops disposed in coaxial alinement, the spaces between adjacent elements forming guide channels for conducting the liquid or

gaseous products of electrolytic decomposi-
tion to and through the open tops of said
elements, and a collector pipe connected to 10
the top of the uppermost element and into
which said products pass from that element.

In testimony whereof I affix my signature.

CARLO ZORZI.
